UNITED STATES PATENT OFFICE.

HARRY W. WETMORE, OF SAN JOSE, CALIFORNIA.

DEVICE FOR PROTECTING THE LIPS OF PLAYERS OF WIND MUSICAL INSTRUMENTS.

1,386,823.

Specification of Letters Patent.

Patented Aug. 9, 1921.

Application filed December 26, 1919. Serial No. 347,325.

To all whom it may concern:

Be it known that I, HARRY W. WETMORE, a citizen of the United States, residing at San Jose, in the county of Santa Clara and State of California, have invented certain new and useful Improvements in Devices for Protecting the Lips of Players of Wind Musical Instruments, of which the following is a specification.

10 This invention relates to a device for protecting the lips of players of wood and brass wind musical instruments against the pressure of the mouthpiece of such instrument against the lips and teeth by affording 15 a smooth surface for the inside of the lips to rest against while playing such instruments, and it has for its object,

First, to provide a device that may be fitted to a person's mouth between the labial 20 surface of the teeth and gums and the inner surface of the lips of either the upper or lower jaw, or both jaws as the case demands, and is held in place by its adaptation to the contour of the teeth and gums of the person 25 to whom it is fitted.

Second, to provide a device that will make the production of good tones easier and is more particularly adapted to persons having receding or protruding lower jaws, rotated, 30 twisted, overlapping, irregular formed or missing anterior teeth of either the upper or lower jaws.

Third, to provide a device for the protection of the lips of players of wood or brass wind musical instruments that may be made 35 of any material suitable, that will overlap the incisal edge of the anterior teeth when necessary for players of reed wind instruments, and that will conform to the labial surface 40 of the anterior teeth and gums and rest against the inner surface of the lips thus forming a smooth surface for the pressure of the mouthpiece against the lips while playing such instruments.

45 With these and other objects in view, my invention resides in the unique construction and arrangement of parts to be hereinafter more fully described and claimed, it being understood that various changes in form, 50 proportion and minor details of construction may be resorted to within the scope of the appended claims.

For a full understanding of the invention and the merits thereof reference is to be had 55 to the accompanying drawings forming a

part of this specification in which similar reference characters represent corresponding parts in all the views.

In the drawings—

Figure 1 is a sectional view through the 60 mouth of a human being showing the device in place, parts in their natural state.

Fig. 2 is a sectional view through the mouth showing the relation of parts when the pressure of the mouthpiece is applied. 65

Fig. 3 is a view of the outer surface of the device.

Fig. 4 is a view of the inner surface of the device showing the ridges and hollows that fit the teeth and gums. 70

Fig. 5 is a sectional view on line 5—5 of Fig. 4.

Fig. 6 is a sectional view on line 6—6 of Fig. 4.

My device for protecting the lips of players of wind musical instruments forming the subject matter of the present invention consists of the small piece of solid substance 1 that may be made of vulcanized hard rubber or other suitable material that may be 80 molded, cast or vulcanized into shape to conform to the labial surface of the anterior teeth 2 and gums 3 of a person to whom it is fitted and that will present a smooth surface 4 for the lips 5 to rest 85 against.

A plurality of ridges are shown at 5^a on the inner surface of the device and are adapted to fit in the crevices between the teeth 2 for holding the device in place. 90

A cornet mouthpiece is shown at 6 pressing the lips 5 against the device as is necessary while playing such instruments.

In case of irregular shaped incisal edges of the anterior teeth 2, the overlapping edge 95 7 of the device affords a straight edge for the assistance of players of reed wind musical instruments.

The disk like piece 1 is constructed to conform to the particular mouth to which it is 100 fitted by, first taking an impression in wax or other suitable material of the part of the mouth to be fitted, it being understood that the device may be fitted to either the upper, lower or both jaws as the irregularity of the 105 teeth and gums of such jaws may require.

After the impression is taken, which is performed in the customary way as in dental practice, a mold is constructed and a cast is made of metal or other hard substance; 110

preferably the mold is packed with vulcanizable dental rubber and vulcanized as is done by dentists in making false teeth plates.

Having thus described my invention what I claim as new and desire to secure by Letters Patent is:

1. A device of the character described consisting of a piece of hard rubber that may be cast into shape, one side of which 10 is adapted to fit against the labial surface of the teeth and gums and the other side resting against the inside of the lips of a person's mouth, said piece of hard rubber having a plurality of ridges on one side 15 fitting between the teeth adapted to serve as anchors for holding the device in place and presenting on the other side a smooth surface for the lip to rest against.

2. A device of the character described 20 consisting of a piece of suitable material that may be molded into shape adapted to fit between the lips and teeth of a person's mouth, said piece of material conforming to the labial surface of the anterior teeth

and gums and presenting on the opposite 25 side a smooth surface for the lip to rest against; an overlapping edge on part of the rim of the disk like piece adapted to overlap the incisal edge of the teeth, thereby presenting a smooth straight edge, substantially 30 as set forth.

3. A device of the character described consisting of a piece of hard rubber that may be cast into shape adapted to fit between the teeth and lips of a person's mouth; 35 a surface on one side of the device conforming to the labial surface of the teeth and gums and presenting on the other side, a smooth surface for the lip to rest against and a straight edge overlapping the incisal 40 edges of the anterior teeth, substantially as set forth.

In testimony whereof I hereby affix my signature in the presence of two witnesses.

HARRY W. WETMORE.
